(57) **CLAIM**

The ornamental design for an LED portable lantern, as shown and described.

DESCRIPTION

FIG. 1 is a right perspective view of an LED portable lantern showing my new design;

FIG. 2 is a left perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a bottom plan view thereof in a modified first position;

FIG. 10 is a right perspective view thereof in an alternative position;

FIG. 11 is a left perspective view thereof in an alternative position;

FIG. 12 is a front view thereof in an alternative position;

FIG. 13 is a rear view thereof in an alternative position;

FIG. 14 is a left side view thereof in an alternative position;

FIG. 15 is a right side view thereof in an alternative position;

FIG. 16 is a top plan view thereof in an alternative position;

FIG. 17 is a bottom plan view thereof in an alternative position;

FIG. 18 is a right perspective view thereof in a second alternative position;
FIG. 19 is a left perspective view thereof in a second alternative position;
FIG. 20 is a front view thereof in a second alternative position;
FIG. 21 is a rear view thereof in a second alternative position;
FIG. 22 is a left side view thereof in a second alternative position;
FIG. 23 is a right side view thereof in a second alternative position;
FIG. 24 is a top plan view thereof in a second alternative position;
FIG. 25 is a bottom plan view thereof in a second alternative position;
FIG. 26 is a bottom plan view thereof in a second alternative position in a modified second alternative position;
FIG. 27 is a right perspective view thereof in a third alternative position;

FIG. 28 is a left perspective view thereof in a third alternative position;
FIG. 29 is a front view thereof in a third alternative position;
FIG. 30 is a rear view thereof in a third alternative position;
FIG. 31 is a left side view thereof in a third alternative position;
FIG. 32 is a right side view thereof in a third alternative position;
FIG. 33 is a top plan view thereof in a third alternative position; and,
FIG. 34 is a bottom plan view thereof in a third alternative position.

The broken lines in the drawings illustrate unclaimed portions of the LED portable lantern and form no part of the claimed design.
